METHOD AND APPARATUS FOR MIXING
AND DISCHARGING THE CONTENTS OF
AN ELECTRIC GLASS FURNACE

John Ferguson, Indianapolis, Ind.

Application June 29, 1934, Serial No. 733,081

18 Claims. (Cl. 13—6)

This invention relates to a method and apparatus for mixing and discharging the contents of an electric furnace which is particularly useful in the manufacture of glass but is equally applicable to other industries.

The principal object of the invention is to produce a furnace in which the material may be discharged in gobs or in a continuous feed without mechanical discharge apparatus and in which a thorough mixing of the ingredients is produced before discharge.

To this end there is provided a furnace having a discharge opening in the floor of the hearth. Electric currents for melting the material on the hearth are passed through the material and a magnetic field is set up which acts magneto-motively upon the current carrying material to assist or impede discharge as may be desired and which acts both magneto-motively and inductively to cause a mixing movement of the material.

Other objects and features of the invention will be understood from the accompanying drawings and the following description and claims:

Fig. 1 is a central sectional view in elevation through an electric furnace constructed in accordance with the invention. Fig. 2 is a sectional view taken on the line 2—2 of Fig. 1. Fig. 3 is a wiring diagram of the electrical connections used with the furnace when it is desired to exert both downward and upward magnetic forces upon the contents of the furnace. Fig. 4 is a vector diagram showing the vector relationship between the currents passing between the electrodes. Fig. 5 is a similar diagram considered at the same instance of time as Fig. 4 showing the vector relationship of the magnetic flux produced between various windings and the voltages applied to said windings. Fig. 6 is a wiring diagram of connections used with the furnace when it is desired to exert only downward forces on the material in the furnace for discharge and to exert alternate upward and downward forces for mixing between periods of discharge. Fig. 7 is a fragmentary sectional view on the line 7—7 of Fig. 2 showing the relation of the internal parts and the furnace charge.

In the drawings, by way of illustration, there is shown a glass furnace having a hearth 10 provided with a shallow dish-shaped floor 11 and a conical dome or roof 12. The roof 12 is supported upon the hearth 10 and the edges thereof are provided with a suitable seal 13, preferably air-tight. Above the dome 12 there is provided a hopper 14 for the batch material to be melted

which communicates with the apex of the dome by means of a passage 15. Within the dome 12 there is provided a conical distributing member 16 supported upon brackets 17 which serves to distribute the batch material to the outer zone of the furnace as described in my copending application, Serial No. 734,247, filed July 9, 1934. Connected to the apex of the distributing member 16 there is a pipe 18 used for drawing off the gases which are the products of the chemical reactions taking place in the formation of glass.

The hearth 10 is provided with a central discharge opening 19. About the periphery of the dish shaped floor 11 there are provided a plurality of electrodes 20A, 20B, 20C, 20A', 20B', and 20C' which are preferably formed of tungsten or other suitable material. Beyond the electrodes there is provided a ring 21 of laminated magnetic material having pole pieces 22 projecting inwardly opposite the spaces between the electrodes. About the ring 21 between each of the pole pieces there are provided windings 23A, 23B, 23C, 23A', 23B', and 23C' which serve, when energized, to magnetize the said ring and to cause magnetic fluxes ϕA , ϕB , ϕC , $\phi A'$, $\phi B'$, and $\phi C'$ to pass between the pole pieces as indicated in the wiring diagrams in Figs. 3 and 6.

The heating current for the batch material is supplied by a transformer 24 herein shown as having its primary windings delta-connected to a set of three-phase power mains 25. One of the secondary windings 26A is connected to the electrodes 20A and 20A', another of said secondary windings 26B is connected to the electrodes 20B and 20B', while the secondary winding 26C is connected to the electrodes 20C and 20C'. The secondary circuits are isolated except within the furnace so that the only currents produced in the glass are diametric currents between the opposite electrodes. It will be noticed that the polarity of the connections between the secondary windings and the electrodes is such that the phase relation of the currents passing between the electrodes is as represented by the vector diagram in Fig. 4. In this diagram, the current passing from electrode 20B to 20B' is indicated by the vector $I(B-B')$, the current passing from the electrode 20A to the electrode 20A' is indicated by the vector $I(A-A')$, while the current passing from electrode 20C to electrode 20C' is indicated by the vector $I(C-C')$. Thus, the currents in the material have a rotating phase relation progressing in a clockwise direction about the furnace.

Since the heating current is substantially a non-inductive load, these currents are substantially in

phase with the secondary voltages induced in the transformer 24.

- For supplying the magnetizing current to the windings 23A, etc. there is provided a second transformer 27 having its primary windings delta-connected to the power mains 25. The secondary windings 28A, 28B, and 28C of said transformer are likewise delta-connected. At a point between the terminals of the secondary winding 28A there is provided a terminal tap AB, a similar terminal tap BC is provided at the corresponding point in the secondary winding 28B, and a similar terminal CA is provided in the corresponding position of the secondary winding 28C. The terminal AB is connected to a stationary contactor 29 in a timing switch 30, the terminal BC is connected to a similar contactor 31, while the terminal CA is connected to similar contactors 32 and 33. The switch 30 is also provided with stationary contactors 34A which in the diagram Fig. 3 are connected to opposite terminals of the windings 23A and 23A'. Similarly in this diagram, contactors 34B are connected to the windings 23B and 23B' and contactors 34C are connected to the windings 23C and 23C'.

The movable portion of the switch 30, indicated diagrammatically at 35, carries a number of contact members 36 which are positioned to engage the stationary contact member in the movement of the switch. In one position of the switch known as the "direct" position, the contact members 36 beneath the letter D in the drawings engage their corresponding stationary contact members. In the reverse position of the switch, the contact members 36 beneath the letter R engage the same stationary contact members. It will be seen that when the switch is in the direct position, the terminals of the windings 23A and 23A' are connected across the taps AB and CA, the terminals of the windings 23B and 23B' are connected across the taps AB and BC, while the terminals of the windings 23C and 23C' are connected across the taps BC and CA. Referring again particularly to Fig. 3, it will be noticed that the left-hand terminal of winding 23A is connected to the same line as the left-hand terminal of winding 23A', while the right-hand terminals of said windings are similarly connected together. Thus, the magnetic flux ϕA will be at its maximum in a clockwise direction while the flux $\phi A'$ is at its maximum in a counterclockwise direction. This insures that the portions of the fluxes ϕA and $\phi A'$ cutting the current path between the electrodes 26A and 26A' exert upward or downward magneto-motive forces upon the current carrying material at the same time. The connections of the windings 23B, 23B', 23C and 23C' are similar.

It is highly desirable that the various magnetic fluxes be in phase with their corresponding heating currents in order to obtain the maximum magneto-motive action. Since the windings 23A, etc. constitute an inductive load, it is necessary that the voltages applied thereto considerably lead the voltages applied to the electrodes to produce the desired phase relation. This is accomplished by the connection herein illustrated since the voltage between terminals CA and AB, for example, considerably leads the voltage generated in the winding 23A which in turn is in phase with the voltage generated in the winding 26A. Thus, the voltages applied to the windings 23A, etc. are in phase relation indicated by the vectors EA, etc. in Fig. 5 which brings the fluxes ϕA , etc. into phase with the currents I(A-A'), etc.

It is obvious that the taps AB, BC, and CA may be placed in any position necessary to provide the leading voltage necessary for the inductance of the magnetizing circuits and may be made adjustable if desired. The magnetic fluxes constitute a rotating magnetic field moving about the furnace in the same direction and in phase with the rotating phase relation of the heating currents.

When the switch 30 is moved to the reverse position R, a study of the diagram will show that each of the windings 23A, etc. is connected to the same terminal taps of the transformer 27 but in the reverse direction. Thus, the direction of the various magnetic fluxes is reversed but the said fluxes still maintain the characteristics of a rotating magnetic field with its direction of rotation unchanged.

By means of this construction, several desirable results are obtained. In one of the positions of switch 30, the magneto-motive forces exerted by the magnetic fluxes upon the current carrying material all act in a downward direction and thus assist the force of gravity in discharging material from the discharge opening 19. In the opposite position of the switch 30 all of the magneto-motive forces act in an upward direction and thus impede the flow of material from the discharge opening 19. At the same time, the rotating magnetic field sets up vertical induced currents in the molten material which act in the same manner as the currents in the rotor of an induction motor and cause the contents of the glass to rotate about the furnace in the direction of rotation of the field. When the field is reversed for discharge, only the polarity is reversed and it still maintains the characteristics of a rotating magnetic field and still maintains the rotary circulation of the glass. The induced currents likewise assist in the heating of the glass so that there is no heat loss resulting therefrom. Thus, the thermal efficiency of the magnetic circuits is a question that need not be considered.

In certain cases, the force of gravity is insufficient to cause the relatively viscous molten glass to be discharged from the furnace so that it is unnecessary that all of the magneto-motive forces act upwardly to prevent discharge. For such cases, the wiring arrangement of Fig. 6 is provided. The only difference between this form of wiring and that of Fig. 3 resides in the fact that the windings 23A', 23B and 23C are permanently connected to their corresponding terminals AB, BC and CA by conductors 39. The windings 23A, 23B' and 23C' are connected through the reversing switch 30 as before. In the operation of this form of the apparatus, when the switch 30 is in the direct position D all of the magneto-motive forces act downwardly to cause discharge of the glass. When the switch is placed in the reverse position R, only the fluxes ϕA , $\phi B'$ and $\phi C'$ are reversed. This reversal causes upward movement of the glass adjacent the electrodes 26A, 26B' and 26C' while the downward movement is continued adjacent the electrodes 26A', 26B and 26C. Since the upward forces substantially balance the downward forces, there is no discharge of the glass but local circulation is set up in the glass due to the upward and downward movements adjacent alternate electrodes. This circulation provides for thorough mixing of the glass between discharge periods while the inductive effect of the rotating

magnetic field during discharge insures a mixing movement at that time.

In Fig. 7 there is illustrated the relation of the internal parts of the furnace to the charge during operation. The incoming batch material 40 substantially covers the magnet ring 21 and extends inwardly beyond the zone of the electrodes. The molten material 41 is confined by the batch pile and is prevented thereby from coming in contact with the magnet ring. Such molten material as may pass beyond the zone of the electrodes as at 42 quickly solidifies due to the reduced temperature beyond the electrodes. Between adjacent electrodes the zone of solid glass and unmelted batch material extends farther into the furnace than is shown in Fig. 7 due to the absence of heating currents. The pole pieces 22 are thus similarly protected against contact with molten material.

20 The heat generated in the windings 23A, etc. is all transmitted to the incoming batch material and, therefore, is not lost from the furnace. Thus, all of the electrical energy supplied to the furnace is put to a useful purpose, either to pre-25 heat the batch, to melt the same, or to produce the desired movements of material within the furnace.

While the foregoing specification describes a preferred form of the invention as applied to a glass furnace, it is apparent that the details thereof may be varied between wide limits without departing from the scope of the invention as defined by the following claims.

The invention claimed is:

- 35 1. In an electric furnace, the combination of a hearth adapted to support a charge of material and having a discharge opening in the bottom thereof, a pair of electrodes positioned on opposite sides of said discharge opening, means for passing an electric current between said electrodes and through said material, and electromagnetic means arranged to produce a magnetic flux transversely cutting the path of said current.
- 40 2. In an electric furnace, the combination of a hearth adapted to support a charge of material and having a discharge opening in the bottom thereof, a pair of electrodes positioned on opposite sides of said discharge opening, means for passing an electric current between said electrodes and through said material, and electromagnetic means arranged to produce a magnetic flux transversely cutting the path of said current in a horizontal plane whereby a vertical magneto-motive force 45 is exerted on the material carrying said current.
- 45 3. In an electric furnace, the combination of a hearth adapted to support a charge of material and having a discharge opening in the bottom thereof, a pair of electrodes positioned on opposite sides of said discharge opening, means for passing an electric current between said electrodes and through said material, electromagnetic means arranged to produce a magnetic flux transversely cutting the path of said current in a horizontal 50 plane whereby a vertical magneto-motive force is exerted on the material carrying said current, and means for reversing the directional relation between said current and said flux whereby said force may assist or impede flow of material 55 through said discharge opening.
- 60 4. In a furnace, the combination of a hearth adapted to carry a charge of an electrically conductive material in a fluid or semi-fluid state, said hearth having a discharge opening in the 65 floor thereof, means for passing a plurality of

alternating currents through said material in diametric paths, means for producing a plurality of alternating magnetic fluxes threading said current paths in a horizontal plane and each exerting a vertical force upon the conducting material 5 in one of said current paths, the phase relation between said currents and said fluxes being such that substantially all of said forces act in the same direction, and means for reversing said phase relation to reverse the direction of said 10 forces for aiding or impeding flow of material through said opening.

5. In a furnace, the combination of a hearth adapted to carry a charge of an electrically conductive material in a fluid or semi-fluid state, 15 said hearth having a discharge opening in the floor thereof, means for passing a plurality of alternating currents through said material in diametric paths, means for producing a plurality 20 of alternating magnetic fluxes threading said current paths in a horizontal plane and each exerting a vertical force upon the conducting material in one of said current paths, the phase relation between said currents and said fluxes being such that substantially all of said forces act in the same 25 direction, and means for varying the effective action of said fluxes for controlling the flow of material through said discharge opening.

6. In a furnace, the combination of a hearth 30 adapted to carry a charge of an electrically conductive material in a fluid or semi-fluid state, said hearth having a discharge opening in the floor thereof, means for passing an alternating electric current through said material, means for producing a pair of alternating magnetic fluxes 35 transversely cutting the path of said current, and means for selectively reversing the phase relation of one of said fluxes, whereby the magneto-motive force exerted thereby on said material may act in the same or in the opposite direction to the 40 force exerted by the other of said fluxes.

7. In a furnace, the combination of a hearth 45 adapted to carry a charge of an electrically conductive material in a fluid or semi-fluid state, said hearth having a discharge opening in the floor thereof, means for passing a plurality of alternating electric currents through said material in diametric paths, said means including a pair of oppositely positioned electrodes for each of said 50 paths, means for producing a plurality of alternating magnetic fluxes, each of said fluxes transversely cutting one of said current paths adjacent one of said electrodes, and means for selectively reversing the phase relation of the fluxes adjacent alternate electrodes, whereby the magneto-motive forces exerted thereby upon said material may act in the same direction as those 55 exerted by the remainder of said fluxes or may act in opposite directions to cause a mixing movement of said material.

8. In a furnace, the combination of a hearth 60 adapted to carry a charge of an electrically conductive material in a fluid or semi-fluid state, said hearth having a discharge opening in the floor thereof, means for passing an electric current through said material, means for producing a pair of magnetic fluxes transversely cutting the path of said current, and means for selectively reversing the directional relation of said fluxes, whereby the magneto-motive forces exerted 65 thereby upon said material may act in the same or in opposite directions.

9. In a furnace, the combination of a hearth 70 adapted to carry a charge of an electrically conductive material in a fluid or semi-fluid state,

8 said hearth having a discharge opening in the floor thereof, means for passing a plurality of electric currents through said material in diametric paths, said means including a pair of oppositely positioned electrodes for each of said paths, means for producing a plurality of magnetic fluxes, each of said fluxes transversely cutting one of said current paths adjacent one of said electrodes, and means for selectively reversing 10 the directional relation of the fluxes adjacent alternate electrodes, whereby the magneto-motive forces exerted thereby upon said material may act in the same direction as those exerted by the remainder of said fluxes or may act in 15 opposite directions to cause a mixing action of said material.

10. An electric furnace including a hearth having a central discharge opening, a plurality of electrodes spaced about the periphery of said 20 hearth, means for passing electric currents between said electrodes, a ring of magnetic material surrounding said electrodes and having pole pieces opposite the spaces between said electrodes, and means for magnetizing said ring to produce magnetic fluxes threading the paths of 25 said currents.

11. An electric furnace including a hearth having a central discharge opening, a plurality of electrodes spaced about the periphery of said 30 hearth, means for passing electric currents between said electrodes, a ring of magnetic material surrounding said electrodes and having pole pieces opposite the spaces between said electrodes, means for magnetizing said ring to produce magnetic fluxes threading the paths of said 35 currents, and means for delivering material to be melted to said furnace in the zone of said magnetic ring, whereby said material protects said ring against excessive heat from the furnace and absorbs heat generated by the magnetizing means.

12. An electric furnace including a hearth having a central discharge opening, a plurality of electrodes spaced about the periphery of said 40 hearth, means for passing electric currents between said electrodes, a ring of magnetic material surrounding said electrodes and having pole pieces opposite the spaces between said electrodes, means for magnetizing said ring to produce magnetic fluxes threading the paths of said 45 currents, and means for maintaining a pile of unmelted batch material substantially covering said ring, the inner edge of said pile being in the zone of said electrodes.

13. A method of mixing material in an electric furnace including the steps of passing electric currents through the material in said furnace, applying magneto-motive forces acting upwardly to parts of the material conducting said currents, and applying magneto-motive forces acting downwardly to adjacent parts thereof.

14. A method of mixing and discharging material in an electric furnace having a discharge opening in the floor thereof consisting of, pass-

ing alternating electric currents through the material in diametric paths, said currents having a rotating phase relation, producing a rotating magnetic field about said furnace, said field acting inductively upon the contents of the furnace 5 to rotate the same and having the proper phase relation with respect to said currents to exert upward magneto-motive forces upon the current carrying material for impeding discharge, and reversing the polarity of said field without reversing its direction of rotation for exerting downward magneto-motive forces on said material to assist in discharge.

15. A method of mixing and discharging material in an electric furnace having a discharge 15 opening in the floor thereof consisting of passing a plurality of electric currents through the material in said furnace, producing a plurality of magnetic fluxes exerting downward magneto-motive forces upon the current carrying material 20 to assist in discharge, and reversing the polarity of some of said fluxes to reverse the direction of some of said magneto-motive forces for impeding discharge and for causing a mixing movement of the material between discharge 25 periods.

16. A method of controlling the discharge of material from a furnace having a discharge opening in the floor thereof consisting in passing a plurality of electric currents through said material in diametric paths, producing a plurality of magnetic fluxes exerting downward magneto-motive forces upon the current carrying material 30 to assist in discharge, and reversing the polarity of at least a part of said fluxes for impeding discharge between discharge periods.

17. A method of controlling the discharge of material from a furnace having a discharge opening in the floor thereof consisting in passing alternating electric currents through the material in diametric paths, said currents having a rotating phase relation, producing a rotating magnetic field about said furnace, said field having the proper phase relation with respect to said currents to exert downward magneto-motive forces on the current carrying material 45 to assist in discharge, and reversing the phase of said field without reversing its direction of rotation to impede discharge.

18. A method of controlling the discharge of material from a furnace having a discharge opening in the floor thereof consisting in passing alternating electric currents through the material in diametric paths, said currents having a rotating phase relation, producing a rotating 55 magnetic field about said furnace, said field having the proper phase relation with respect to said currents to exert downward magneto-motive forces on the current carrying material to assist in discharge, and reversing the polarity 60 of at least a portion of said field to impede discharge between discharge periods.

JOHN FERGUSON.
